UNITED STATES PATENT OFFICE.

GUSTAV NORMAN, OF ABERDEEN, WASHINGTON.

GARTER OR GARMENT FASTENER.

1,272,079.

Specification of Letters Patent.

Patented July 9, 1918.

Application filed November 15, 1916. Serial No. 131,545.

To all whom it may concern:

Be it known that I, GUSTAV NORMAN, a citizen of the United States, residing at Aberdeen, in the county of Chehalis, State 5 of Washington, have invented a new and useful Garter or Garment Fastener; and I do hereby declare the following to be a full, clear, and exact description of the invention, such as will enable others skilled in the art 10 to which it appertains to make and use the same.

This invention relates to a useful and improved garter or garment fastener, and one of the objects of the invention is to improve, 15 simplify and render more practical the fastener, clamp or clasp set forth, claimed and illustrated in the patent to Gustav Norman, dated July 22, 1913, Patent Number 1,067,835.

Another object of the invention is to provide a fastener, clamp or clasp, which may be employed in connection with a circular garter, but preferably to be connected to the lower end of a garter extending from a pair 25 of corsets or the like.

A further object of the invention is to provide a clamp or clasp having a base clamping jaw, a holding and releasing clamping jaw loosely carried or pivoted to an auxiliary pivotally mounted plate or lever (which is pivotally mounted upon the base clamping jaw) so that when the auxiliary plate or lever is moved toward the base clamping jaw, the releasing and holding clamping 30 jaw will be forced between the pivot of the base clamping jaw, to clamp one end of the garter or an edge of the garment between the flange and the holding and releasing jaw.

Another object of the invention is to provide a flange on the pivoted end of the pivotally mounted plate or lever, the resiliency or yieldability of which in co-operating with a tongue of the holding and releasing jaw, 40 will hold the lever or plate closed.

In practical fields, the details of construction may necessitate alterations, falling within the scope of what is claimed.

The invention comprises further features 50 and combination of parts, as hereinafter set forth, shown in the drawings, and claimed.

In the drawings:

Figure 1 is a view in perspective of the improved fastener, clamp or clasp, as ap- 55 plied to a corset garter.

Fig. 2 is a plan view of the fastener or clamp.

Fig. 3 is a sectional view on line 3—3 of Fig. 2, showing the releasing and holding jaw closed.

Fig. 4 is a view similar to Fig. 3, showing the holding and releasing jaw partly opened.

Fig. 5 is a similar sectional view showing the holding and releasing jaw entirely opened.

Fig. 6 is a detail perspective view of the auxiliary plate or lever.

Fig. 7 is a detail perspective view of the holding and releasing clamping jaw.

Fig. 8 is a view in perspective of the preferred form of fastener or clasp.

Referring more especially to the drawings, 1 designates a garter, which may be either a man's garter, or a garter extending from the edge of a pair of ladies' corsets, 75 and one end of this garter may be turned to form a loop 3, held by a clasp 2, as shown in Fig. 1, or the lower end of a garter may be attached permanently to the base clamping jaw of the clamp or fastener, as shown 80 in Fig. 8. In Fig. 1, the base clamping jaw or plate 5, has a transverse slot 4 at its upper end, to receive the loop 3 of the garter, whereby the garter, by virtue of the clasp 2, may be adjusted. However, in Fig. 85 8, a piece of fabric 2^a is inserted through the slot 4 and folded, as shown in dotted lines c in Fig. 8, and is stitched securely between adjacent pieces a and b of the garter. The base clamping jaw 5 adjacent the 90 slot 4 is provided with a second slot 4^a. A piece of an elastic fabric or the like 4^b is passed through the slot 4 and stitched at 4^a and 4^b, the stitches 4^a passing through the slot 4^a. This piece of elastic fabric is pro- 95 vided for the purpose of covering the inner face of the base clamping jaw, to prevent the metal from contacting with the bare leg of the wearer. In Fig. 8, the elastic fabric 4^b is stitched in any suitable manner at its upper end between the two pieces a and b of the garter 1. The base clamping jaw 5 near the slot 4 is provided with a pair of lateral ears 6, which are provided with apertures. The auxiliary plate or lever 9 105 is provided with side flanges 8, of the shape shown in the drawing, particularly in Fig. 6. The corresponding ends of the flanges 8 are provided with laterally extending pivot lugs 10, which engage the apertures 110

of the ears 6 of the base clamping jaw, thereby pivotally mounting the lever 9. Projecting from one crotch end of the opening 12^a of the lever 9, and extending laterally is a projection 11 having laterally extending lugs 12. In other words, the projection 11 is T shaped and extends through the opening 13 of the holding and releasing plate or jaw 14. It is to be also noted that 10 the opening 13 is T-shaped, so that when connecting the auxiliary plate or lever 9 to the holding and releasing clamping jaw, the transverse elongated portion of the projection 11 will pass through the transverse 15 elongated part 15 of the opening 13, so that the contracted part of said projection will engage the restricted portion of the opening 13, as shown clearly in Figs. 3, 4 and 5. One end of the holding and releasing clamp- 20 ing jaw has a laterally extending flange 16, from which a tongue 17 projects, which tongue is angular, and yieldable. The lever 9 at its pivoted end is provided with a flange 10^a, which is yieldable, particularly adja- 25 cent the opening 12^a, and the yieldable or spring action in said tongue 17 and said flange 10^a, particularly said tongue (which co-operates with the flange) will hold the lever down upon the holding and releasing 30 clamping jaw, when it is closed. The tongue 17 terminates in a flange 18, which overlies the outer edge of the flange 10^a, to more securely hold the lever closed. The lower end portion of the base clamping jaw 35 terminates in a flange 19, and the lower end of the elastic piece 4^b extends over this flange and has its extremity secured to the end of the flange 19, by bending the extreme end edge portion 20 of the flange 19 over 40 and clenching the same on the extremity of the elastic piece, as shown in the drawings. By so securing the elastic piece to the flange 19, a suitable shield or cover is afforded, thereby preventing excessive wear on the 45 hose or other garment, which is clamped between the flange 19 and the free end of the releasing and holding clamping jaw. The free extremity of the holding and re- 50 leasing jaw terminates in a flange 21, which is provided with an angular portion 22, the part 23 of which fitting between the base clamping jaw and the clenched portion of the elastic piece. By so constructing the free extremity of the holding and releasing 55 clamping jaw, means is provided, between the portions 21, 22 and 23 and the flange 19 and the clenched portion of the elastic piece, by which the hose or other garment may be clamped. Further, by the provision 60 of the parts 21, 22 and 23, means is provided which will prevent extreme wear on the hose or other garment. The holding and releasing jaw is provided with a shoulder 24 on each side, as shown in Figs. 1 to 7, inclusive. 65 These shoulders are engaged by the flange

end portions 25 of the plate lever 9. In Fig. 8, however, there is only one shoulder 24 extending transversely of the holding and releasing jaw, and which shoulder is engaged by the single flange 26 of the plate 70 lever 9. By the provision of the shoulder 24, which extends outwardly farther than the flanges 25 or flange 26, prevents the flanged end 26 from catching or engaging some foreign object and pull the lever 9 out- 75 wardly, which will release the garment. When the parts of the clamp or fastener, are disposed as shown in Fig. 3, a garment or the like may be clamped between the flange 19 and the parts 21, 22 and 23. When the 80 auxiliary plate lever 9 is moved to the position shown in Fig. 5, the holding and re- leasing jaw is held supported at right angles to the auxiliary plate lever, by virtue of said lugs 12 and said flange 16. 85

The invention having been set forth, what is claimed as new and useful, is:—

1. In a device as set forth, a base clamp- 90 ing jaw having a shield on one face to prevent the contact of the metal with the leg of the wearer, one end of said jaw having an outwardly turned flange, an auxiliary lever pivotally mounted near the other end of said jaw and provided with a rectangular opening adjacent its pivoted end, one edge of said opening having a laterally extending T-shaped lug, said lever having at its pivoted end a transversely disposed yieldable flange, a holding and releasing clamping jaw having at one end an angle 100 flange adapted to be jammed under the outwardly turned flange of the first jaw, and provided at its other end with a T-shaped slot in which said T-shaped lug engages for loosely connecting said holding and re- 105 leasing jaw to said lever, whereby as the lever is closed the angle end flange of said holding and releasing jaw is forced in en- gagement with and under the outwardly extending flange of the first jaw, said hold- 110 ing and releasing jaw having a yieldable tongue adjacent said T-shaped opening, said tongue being bent U-shaped in cross section and extending through the opening of said lever and provided with a terminal flange 115 adapted to engage the edge of the flange of the lever whereby the lever is held against said holding and releasing jaw when closed.

2. In a device as set forth, a base clamp- 120 ing jaw, one end of which having an out- wardly turned flange, an auxiliary lever pivotally mounted near the other end of said jaw and provided with a rectangular opening adjacent its pivoted end, one edge 125 of said opening having a lateral T-shaped lug, the pivoted end of said lever having a yieldable flange opposite said lug, a holding and releasing clamping jaw, one end of which is adapted to engage said outwardly 130

turned flange and its other end portion provided with a T-shaped slot to be loosely engaged by the T-shaped lug for loosely connecting the second jaw to the lever, the 5 loosely connected end of the second jaw having a yieldable tongue being bent U-shaped and extending through the rectangular opening and having a terminal flange engaging said yieldable flange of the lever for holding the lever against the second jaw when closed.

In testimony whereof I have signed my name to this specification in the presence of two subscribing witnesses.

GUSTAV NORMAN.
